UNITED STATES PATENT OFFICE.

ARCHIBALD HEWLETT GREEN, OF LONDON, ENGLAND, ASSIGNOR TO THE INTERNATIONAL SILENCER COMPANY (1926) LIMITED, OF COUNTY OF LONDON, ENGLAND, A BRITISH COMPANY.

SILENCER FOR GASEOUS CURRENTS.

Application filed July 27, 1926, Serial No. 125,215, and in Great Britain June 12, 1925.

This invention is an improvement in or modification of the invention which is the subject of Patent No. 1,554,534, relating to silencers for gaseous currents, such as are produced in the exhaust of internal combustion engines. Such a silencer as described in the specification of the said Patent No. 1,554,534 comprised a transversely divisible silencer body or casing of cylindrical shape at its middle part and of reduced diameter at its end into which was fitted a filling consisting of a permeable homogeneous mass of metal of a resilient character such as very narrow and thin strips of flexible metal, enclosed in a reticulated metal bag. In order to prevent the filling from being compressed towards the outlet end of the silencer by the impact of the entering gases, it was proposed in the specification of Patent No. 1,575,657 to provide an inner casing transversely divisible into two approximately conical shells each having at its base an annular enlargement to fit into sockets in the outer casing, each of the said shells being perforated, and the filling being enclosed within the said inner casing. This arrangement, however, reduced the space within the silencer body available for containing the filling, and it is the object of the present invention to minimize such reduction while retaining the advantages of the inner casing.

According to the present invention a perforated metal cup is inserted into the transversely divisible silencer body, into which it fits at or near the inlet end, against which cup the bag containing the strip metal or other filling is packed. A perforated paraboloidal, conical, or similarly shaped shell or inner casing of the kind described in the specification of Patent No. 1,575,657 is secured within the silencer with its apex directed towards the outlet to receive the other end of the filling. The said shell may be secured in position by means of a flange entering between the opposing rims or flanges of the separate parts of the silencer body in the manner described in the specification of Patent No. 1,575,657. The bag can thus be of greater capacity than that previously used. A large portion of the surface of the filling bag is thus in contact with the interior of the silencer body, and the gases enter and traverse the filling longitudinally,

escaping more or less radially through the perforations in the conical shell. 55

In order that the said invention may be clearly understood and readily carried into effect, the same will now be described more fully with reference to the accompanying drawings, wherein:— 60

Figure 1 represents in longitudinal section a silencer exemplifying this invention.

Figure 2 is a transverse section taken on the line 2—2 in Figure 1.

The two halves or separable portions of the silencer casing are indicated at A and B, the part A being the one intended to be secured on the exhaust pipe. E indicates a tapered shell or inner casing having its apex pointing toward the outlet and an enlargement e' at its base secured within the rim b' of the casing B, this shell E having perforations at e''. A perforated metal cup H is fitted at the shoulder a' of the casing A to overlap the end of the filling bag. The filling J contained in a reticulated metal bag K is pressed into the casing A so that it rests against the cup H, after which the shell E and casing B are placed in position and the latter secured by the ring C fitting over the enlarged rims a', b' of the casing members A and B, which ring is then tightened by means of a wing-nut at e'. The gases passing through the cup H traverse the filling longitudinally and escape through the perforations e'' and thence through the silencer outlet b''. 85

What I claim and desire to secure by Letters Patent of the United States is:—

1. In a silencer for gaseous currents, comprising a body portion built of readily detachable sections, said body portion having a reduced neck at each end, and a filling consisting of a permeable homogeneous tangled mass of very narrow and thin ribbons of flexible metallic material enclosed in a metal bag made of foraminous reticulated sheet material adapted to fit bodily into the said body portion, the combination therewith of a rigid perforated metal cup inserted into the neck at the end of said body at which the gases enter, the convex side of said cup facing the incoming gases. 95

2. In a silencer for gaseous currents, comprising a body portion built of readily detachable sections, said body portion hav-

ing a reduced neck at each end, and a filling consisting of a permeable homogenous tangled mass of very narrow and thin ribbons of flexible metallic material enclosed in a metal bag made of foraminous reticulated sheet material adapted to fit bodily into the said body portion, the combination therewith of a rigid perforated metal cup inserted into the neck at the end of said body 10 at which the gases enter, the convex side of said cup facing the incoming gases and an additional perforated metal member located between the filling and the outlet end of the silencer body.

15 3. In a silencer for gaseous currents, comprising a body portion built of readily

detachable sections, said body portion having a reduced neck at each end, and a filling consisting of a permeable homogenous tangled mass of very narrow and thin ribbons of flexible metallic material enclosed in a metal bag made of foraminous reticulated sheet material adapted to fit bodily into said body portion, the combination therewith of a rigid perforated metal cup 20 inserted into the end of said body at which the gases enter and of a perforated approximately conical shell secured within the silencer and adjacent the outlet end thereof with its apex directed towards the outlet.

ARCHIBALD HEWLETT GREEN.
